UNITED STATES PATENT OFFICE.

CORNELIUS C. STEWART, OF PHILADELPHIA, PENNSYLVANIA.

EVACUATOR.

Application filed November 17, 1920. Serial No. 424,801.

To all whom it may concern:

Be it known that I, CORNELIUS C. STEWART, a citizen of the United States, residing in Philadelphia, Pennsylvania, have invented 5 certain Improvements in Evacuators, of which the following is a specification.

My invention relates to evacuators of the type employed in connection with the driers of paper making machines for removing 10 from the drier the water resulting from the condensed steam employed in the drying process.

One object of my invention is to provide an improved method of construction possessing 15 the advantages of great simplicity and low production cost, a further object being to so construct the evacuator that a free and unobstructed passage for the water is provided.

20 In the attached drawings:

Figure 1, is a plan view of an evacuator with the top plate removed, made in accordance with my invention;

25 Fig. 2, is an elevation of the assembled evacuator;

Fig. 3, is a partial plan view of the top plate showing the intake port and the scoop;

Fig. 4, is a partial section of the evacuator on the line 4—4, Fig. 1;

30 Fig. 5, is a partial section on the line 5—5, Fig 1;

Fig. 6, is a detached perspective of corresponding halves of the top and bottom plates;

35 Fig. 7, is a perspective of one section of the partition, and

Fig. 8, is a partial section illustrating a modification of the attaching means for the top and bottom plates.

40 With reference to the drawings, my evacuator consists of a hollow drum 1 having extending between the two faces thereof on the inside a spirally arranged partitioning wall 2, as most clearly illustrated in Fig. 1, 45 said wall extending substantially from the periphery to a point near the center of the drum. An aperture 3 is formed in one face of the drum, in the top plate 1^a in the present instance, substantially at the periphery

50 thereof for the admission of water or other liquid to the interior of the drum, and a discharge port 4 is formed in the center, preferably of the opposite face of the drum, as in the present instance in the bottom plate 1^b. A suitable scoop 5 is established at the admission opening 3 whereby when the drum

is revolved the liquid is guided into the said aperture, said liquid after entering the drum being carried to the center through the spiral passage formed by the partition 2, and 60 being finally discharged through the port 4. The device and its method of operation is well known to those acquainted with the art.

In the construction of my evacuator, I preferably form the drum casing of four 65 substantially semicircular portions, two of said semicircular portions forming together one face and the sides of the drum, and the other two constituting the opposite face. One of each of these pairs of semicircular 70 portions are shown in Fig. 6, the portion 6 comprising a semicircular disk 7 having extending from the curved edge thereof a flange 8 and from the straight edge thereof but in the opposite direction a flange 9, 75 while the lower portion 10 comprises a disk 11 corresponding to the disk 7 and having extending from the straight edge thereof a flange 12. These portions are adapted to fit together, the lower edge of the flange 8 meeting in the present instance the curved edge of the disk 11, and in the form shown in Fig. 4, the portions are adapted to be secured together by welding along these meeting edges of the said flange and disk. These 80 two portions, 6 and 10, together form substantially one-half of the drum casing, the opposite half being formed by corresponding but oppositely constructed semicircular portions 6^a and 10^a. 90

The respective halves of the drum casing thus formed may be secured together by bolts 13 passing through the flanges 9 and 9^a, and the corresponding flanges 12 and 12^a respectively upon the other half. Washers 95 or gaskets 14 placed between the flanges renders the joint entirely watertight, while to further strengthen the construction, reinforcing straps 15 may be employed, one bearing against each of the outer faces of the 100 flanges.

The respective casing portions are preferably stamped from sheet metal of the requisite thickness, recesses 16 being formed at the same time in the inside of the disk portions which constitute the faces of the drum, these recesses 16 being formed by pressing up the metal from the inside of the said disk portions, as most clearly illustrated in Figs. 4, 5, and 6. When the drum portions are assembled, these recesses are such as to form in each face thereof a continuous spiral starting at a 105 110

point substantially at the periphery of the drum and advancing to a point near the center, the spirals being identical in the two faces and symmetrically arranged with respect to each other. The function of these recesses is to receive and retain in position the element or elements which constitute the partitioning wall 2. The said partitioning wall 2 is preferably made in substantially 5 semicircular segments 2^a, as shown in Fig. 7, such that there is a segment for each corresponding pair of grooves in the respective halves of the drum casing. Thus, the respective halves of the casing being formed in 10 the manner previously described, the semicircular sections 2^a of the partitioning wall 2 are inserted in their respective grooves, this being done by placing one end of the said partition sections in the exposed ends of the 15 grooves where they meet the straight sides of the disks in which they are formed, and pushing the said partition section inwardly until it has assumed its proper position. The partitions being in place, they may be 20 secured to the casing by spot welding along the backs of the grooves. Where the sections of the casing are joined together, as illustrated in Fig. 7, in such manner that they may be disassembled, it is preferred that in 25 each case the partition sections be welded to the casing along one edge only and that the welded edges alternate in alternate sections from one face of the casing to the other. In this manner, the said partition sections will 30 be secured in alternation to opposite sides of the casing, and an equal number of sections will be attached to each of the four portions of the casing, greater rigidity and strength resulting. The modification illustrated in 35 Fig. 8, shows a flange 8^b which rests upon the inner surface of the disk 11, said flange and disk being secured together by means of bolts 17 which pass therethrough. A gum gasket 18 inserted between the flange and the 40 disk makes a water-tight joint.

It will be noticed that the corresponding flanges 8 and 8^a upon the portions 6 and 6^a, respectively, and the partition sections 2^a are extended so as to overlap when the evacuator is assembled, so that a close joint is 45 formed between the respective sections. It will also be noticed that in order to allow for the discharge port 4, it is necessary to cut away a portion of the flange 9 at the center, 50 said cut-away portion being such as to permit also the addition of a flange 19, which may be attached by means of bolts 19^a around the aperture 4, as clearly shown in Fig. 5, this flange being for the reception of a suitable pipe for carrying away the discharged 55 water.

It will be understood that considerable modification of the invention is possible with no departure from the essential features of the invention. It is not intended for example that the invention shall be limited to grooves or recesses formed in the body of the casing itself, since grooves suitable for the reception of the partition wall may be made in numerous ways.

I claim:

1. An evacuator comprising a hollow drum, the faces of said drum having correspondingly disposed spirally arranged grooves in the inside thereof, partitioning 75 walls in said grooves, and openings in said drum for the admission and exhaust of a liquid.

2. An evacuator comprising four substantially flat and semicircular elements having 80 integral flanges extending from the straight edges thereof whereby the said elements may be connected in pairs, integral flanges extending from the curved edges of two of said elements and adapted to be attached along 85 their edges to the said other elements to form a hollow drum of which the said latter flanges constitute the sides, grooves on the inside of the faces of said drum, said grooves being such as to form corresponding and 90 substantially continuous spirals on the respective faces extending substantially from the periphery to the center thereof, a partitioning wall established in said grooves, a port at the periphery of the drum, and a 95 port at the center of one of said faces.

3. An evacuator comprising four semicircular flanged elements attachable in pairs to form respectively one half of a hollow 100 drum, means for uniting said halves to complete the said drum, grooves on the inner faces of said elements and so arranged that when the drum is assembled said grooves form corresponding and substantially continuous spirals on the faces of said drum, said spirals starting substantially at the periphery of the drum and ending at a point 105 near the center, semicircular partition elements established in said grooves, an admission port at the periphery of the drum, and an exhaust port at the center of one of the said faces.

4. In an evacuator, a hollow drum comprising substantially semicircular portions adapted for detachable connection with each other, and partitioning elements in each of said portions adapted when the latter are connected to form a substantially continuous spiral partition extending substantially 115 from the periphery of the drum to a point 120 near the center.

CORNELIUS C. STEWART.
